E. F. NIEDECKEN

WASTE MECHANISM

Original Filed May 5, 1920

UNITED STATES PATENT OFFICE.

EDWARD F. NIEDECKEN, OF MILWAUKEE, WISCONSIN, ASSIGNOR TO HOFFMANN & BILLINGS MANUFACTURING COMPANY, OF MILWAUKEE, WISCONSIN, A CORPORATION OF WISCONSIN.

WASTE MECHANISM.

Original application filed May 5, 1920, Serial No. 378,995. Divided and this application filed February 3, 1923. Serial No. 616,718.

To all whom it may concern:

Be it known that I, EDWARD F. NIEDECKEN, a citizen of the United States, residing at Milwaukee, in the county of Milwaukee and 5 State of Wisconsin, have invented certain new and useful Improvements in Waste Mechanism, of which the following is a specification, reference being had to the accompanying drawing, forming a part there- 10 of.

This invention relates to waste mechanism for bath tubs and similar receptacles and the object of the invention is to improve the construction and operation of waste mechanism 15 in the manner to be hereinafter described and claimed, this application being a division of my prior application for Letters Patent for improvements in waste mechanism, filed May 5, 1920, Serial Number 20 378,995.

Referring to the drawings which accompany this specification and form a part hereof, which drawings illustrate an embodiment of this invention, and on which 25 drawings the same reference characters are used to designate the same parts in each of the views, Fig. 1 is a vertical section of the waste mechanism, parts being shown in elevation; and Fig. 2 is a vertical section taken 30 on the line 2—2 on Fig. 1, looking in the direction indicated by the arrows.

Referring to the drawings, the reference numeral 1 designates a bath tub, or liquid receptacle, which is provided with an outlet 35 aperture 2 and an overflow aperture 3. A pipe connection 4, which is provided with a flange 5, is screwed into the elbow 6 and a packing 7 makes a fluid tight joint. The elbow 6 is connected with the stand pipe 8 in line with a tubular valve 9. The valve 9 has an upper, circumferential valve face 10 and a lower, circumferential valve face 11. The upper valve face 10 projects beyond the 40 body of the valve and the lower valve face 11 is arranged within the circumference of the body of the valve so that the valve may be 45 readily assembled or disassembled. Inwardly projecting valve seats 12 and 13 are provided for the valve faces 10 and 11. It will 50 be readily seen from an inspection of Fig. 1 of the drawings that, with this construction when the valve 9 is closed, fluid cannot escape from the receptacle 1 either up or down past the valve 9 while fluid overflowing is 55 free to pass through the valve 9. The valve

body 14 is preferably provided with a guide or steady flange or rib 15 which is located opposite the elbow 6 to guard against displacement or binding of the valve 9 when the valve is partly opened and fluid is running to waste through the elbow 6. The tubular body 16 of the valve 9 makes a substantially close fit within the valve seat 12 to prevent fluid from rising past the valve 9 and fouling the interior of the stand pipe 8 and the parts at the lower end thereof. This construction makes the mechanism sanitary 60 and reliable. The valve seat 12 serves as a scraper to remove deposits on the exterior of the valve 9 and, as it is very short vertically, 70 there is no opportunity for soap, for example, to work in between the valve and the seat and produce corrosion, sticking and wear.

The valve 9 can be raised and lowered in 75 any suitable manner. The drawings illustrate a knob 17 connected with the valve and studs 18 and 19 projecting into inclined grooves in a member at the top of the stand pipe so that the valve can be opened and 80 closed and can be held open in a common and well-known manner.

One of the difficulties heretofore encountered in installing bath tub wastes has been due to the different inclinations of the ends 85 of bath tubs in which the overflow apertures were located. I overcome the difficulty by using an overflow pipe 20 which projects into a pipe connection or nipple 21 on the stand pipe 8 and which is made smaller than 90 the interior of the nipple so that it can be turned out of direct line with the nipple. A packing 22 makes a fluid tight joint and the follower 23 is bored larger than the pipe 20. The pipe 20 is provided with a flange 24 to seat against the bath tub, and the joint is 95 made tight by a packing 25. A rod 26 is screwthreaded at both ends and is screwed into a nut 27, passes through the grating 28 and is provided with a nut 29 on its end bearing against the grating. The nut 27 is movable within the nipple 21 so that the rod 26 can assume different angles. The drawings illustrate the nut 27 as pivoted on pivot screws 30 and 31, which are screwed into the 100 nipple 21 and engage with recesses in the nut 27.

The advantages of the invention are of great importance from practical and sanitary standpoints. One standard overflow 105

fitting can be properly and effectively secured to bath tubs, or receptacles, the inclinations of the ends of which vary.

The valve body 14 is provided with the waste inlet 32 and the stand pipe 8 is provided with the overflow inlet 33 above the waste inlet 32. The stand pipe 8 and the waste pipes 34 and 35 are illustrated by the drawings as connected with the valve body 14 by means of slip joint connections to illustrate a practical and convenient method of making pipe connections.

What I claim is:

1. In waste mechanism, the combination with an overflow nipple of an overflow pipe of smaller size than the nipple, means to make a tight joint between the overflow pipe and the nipple, and means movable with respect to the nipple to connect the nipple and the overflow pipe to a receptacle.

2. In waste mechanism, the combination with an overflow nipple of an overflow pipe of smaller size than the nipple, means to

make a tight joint between the overflow pipe and the nipple, and a rod movably connected with the nipple to secure the nipple and the overflow pipe to a receptacle.

3. In waste mechanism, the combination with a pipe connection, an overflow pipe connected to said connection, and a rod arranged in said connection and said pipe to connect the same to a receptacle, of a member secured to an end of said rod and pivotally connected to said connection.

4. In waste mechanism, the combination with a pipe connection, an overflow pipe connected to said connection, and a rod arranged in said connection and said pipe to connect the same to a receptacle, of a nut threaded upon an end of said rod, and screws passing through said connection into opposite sides of said nut whereby the latter is pivotally connected to said connection.

In witness whereof I hereto affix my signature.

EDWARD F. NIEDECKEN.
